CLAIM

I claim the ornamental design for a television remote control, as shown and described.

DESCRIPTION

FIG. 1 is a front elevation view of the television remote control showing my novel design;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in FIG. 2 depict portions of the remote control that form no part of the claimed design.
